METHOD AND APPARATUS FOR DETECTING
HEAT

Vladimir K. Zworykin, Philadelphia, Pa., and

Corporation of America, a corporation of Dela-
ware

Application May 7, 1936, Serial No. 78,344

2 Claims. (Cl. 250—166)

This invention relates to methods of, and apparatus for, detecting and measuring heat and particularly to electrical means for measuring degrees of heat within and above those indicated by the mercurial thermometer.

The invention contemplates and its construction provides an electron multiplier including a primary electron source, or cathode, which emits electrons when subjected to radiant heat. The emission of primary-electrons may be purely thermionic or it may be brought about by utilizing the infra-red rays in the heat. The primary stream of electrons whether produced by the infra-red rays or thermionically is caused to impinge upon the multiplying electrodes of an electron multiplier whereby the number of electrons is augmented and the output of the multiplier raised to a level suitable for operating an indicator, measuring device, or relay.

20 The multiplier may conveniently be of the general type disclosed in French Patent 582,428 or of the type disclosed in the copending application of Louis Malter, Serial No. 4,049, filed January 30, 1935 and assigned to Radio Corporation of America. In the above-identified copending application there is disclosed a multi-stage electron multiplier constituted by a plurality of pairs of opposed electrodes axially disposed in an evacuated container with their faces lying in parallel planes. For convenience the electrodes may be designated respectively, "upper" or "accelerating" and "lower" or "multiplying". Preferably the faces of the multiplying electrodes are specially treated as by photosensitization to enhance their ability to emit secondary electrons and a primary electron source photoelectric or thermionic in character is provided. In addition electro-magnetic means are provided for the purpose of causing the electrodes to describe approximately trochoidal paths from each electrode to the next adjacent electrode, thus permitting the use of high accelerating potentials on the upper electrodes without the disadvantages resulting from the space charges encountered in a device according to the French patent.

The ratio of the number of secondary electrons to the number of primary electrons depends in part upon the character of the emissive surface and upon the potential difference between the surface and the source of the electrons. This ratio can be made considerably greater than unity. For example, a ratio of three, six, or more secondary electrons to one impinging electron is readily obtainable with

metallic surfaces treated in known ways and subjected to discharges at potentials of 300 to 400 volts.

If the secondary electron current, in turn, is caused to impinge with sufficient velocity upon a further electrode with a suitably treated surface, the ratio of secondary emission from the second multiplying electrode may also be greater than unity. Hence, one is able to obtain with "n" multiplying electrodes in cascade, for example, an amplification of the original or primary electron current equivalent to the amplification per electrode raised to the *n*th power. A millionfold amplification is readily obtained in a single device.

The novel features characteristic of the present invention are set forth with particularity in the appended claims. The invention itself, however, both as to its organization and method of operation will best be understood by reference to the following description taken in connection with the accompanying drawing in which

Figure 1 is a view in perspective of a heat-indicator embodied in an electric discharge device of the type described in the Malter application, portions of the container wall and the associated magnetic field structure being broken away to more clearly illustrate the disposition and mounting of the electrodes;

Fig. 2 is a view in perspective of another form of radiant-heat responsive cathode; and

Fig. 3 is a diagrammatic view of a device, connected in circuit, and which employs an auxiliary heater for the cathode.

Referring now to Fig. 1 of the drawing, an electron multiplier embodying the invention is constituted by a cylindrical evacuated container T of glass, "Pyrex" or other suitable material wherein is disposed a plurality of electron emissive lower electrodes designated 1, 3, 5, 7 and 9, respectively, lying in the same plane and spaced apart along the long axis of the container and a plurality of upper or accelerating electrodes 2, 4, 6, 8 and 10 disposed in a plane parallel to and spaced from the plane in which lie the first-mentioned electrodes.

The upper and lower electrodes are grouped, vertically in pairs. All of the electrodes have substantially the same length-breadth dimensions and they are spaced apart substantially the same distance along the long axis of the container. Such configuration is desirable in that it permits accurate electron-path-control by means of a single magnetic field.

Each electrode is provided with an external

lead "a" individual thereto. If desired the electrodes of each set (i. e., "upper" and "lower") may be constructed as elements of a sub-assembly and each introduced into the tube as a unit as taught by the earlier Malter disclosure, or they may be arranged as elements in a unitary supporting assembly as disclosed in copending application to Ernest Massa and Louis Malter, Serial No. 33,996 filed July 31, 1935, and assigned to Radio Corporation of America.

An output electrode 12 is mounted in one end of the tube, preferably fairly close to the sets of electrodes and in a plane transverse to the tube axis. The output electrode is provided with a terminal connection 12a which extends through the wall of the container to the outside thereof.

The upper electrodes are preferably made of molybdenum, tantalum, nickel or any other metal which is easily de-gassed and not easily oxidized. The accelerating electrode 2 which is paired with the primary-electron emitter or cathode 1 is suitably orificed as at 2b to permit passage of heat rays.

The lower electrodes are preferably made of silver. With the exception of the cathode 1 they may be of substantial and uniform thickness. The cathode 1 is the heat responsive primary-electron emitting electrode and is formed of a very thin sheet, say of the order of .0002" of silver foil, conveniently supported or backed by a strip of mica 1b or other rigid poor heat conducting substance. It may, however, be constituted by a sheet of mica 21b having deposited thereon, as by spraying, a mere film 21 of silver, as indicated in Fig. 2. Surfaces of both types emit thermionic electrons at comparatively low temperatures. With either construction the heat conduction to the supports is negligible, the only heat lost being due to radiation.

In manufacturing the device of Fig. 1 the electrodes are first suitably mounted and the tube T is then heated and evacuated. After evacuation, oxygen is introduced into the container at a pressure in the neighborhood of 1 mm. of mercury. One of the "upper" or accelerating electrodes is then made substantially 500 volts positive with respect to its corresponding lower electrode to cause a glow discharge which oxidizes the surface of the lower electrode. The oxidation is carried on until the lower surface acquires preferably a bluish-green tinge. Each pair of electrodes is treated in the same manner and the process is continued until all of the lower electrodes, including the cathode, have acquired an oxide surface.

After the lower electrodes are oxidized the residual oxygen is pumped out of the container and an alkali metal is distilled into it. For this purpose caesium is preferred, sodium, rubidium or potassium may, however, be employed. The tube is next baked for about ten minutes at a temperature of 210° C., which causes the alkali metal to combine with the silver oxide, thus giving rise to a highly sensitive electron-emissive surface. During the baking step the excess caesium is pumped out of the device.

During the heating process just mentioned any caesium or other alkali metal which is deposited upon the upper electrodes or upon the container walls is driven off and whatever caesium is not removed by the pumping may be taken up if desired by a small amount of lead oxide which, though not shown in the drawing, may be introduced into the container at the time the electrodes are mounted therein. The lead oxide

forms a relatively stable compound with the excess caesium and prevents it from being redeposited on the inner walls of the container where it would provide leakage paths upon the electrodes.

Any convenient means may be utilized for establishing a magnetic field parallel to the electrode surfaces such, for example, as the device M. Preferably this device M is constituted by an U-shaped element 25 of magnetically permeable material on which is mounted an energizing coil 27 and to each upstanding portion of which is a fixed plate 29 also of permeable material. The tube is disposed between these plates in such position that a substantially uniform magnetic field is set up parallel to the opposed surfaces of the sets of electrodes. Any convenient source of uni-directional potential may be used to supply field current to the coil 27. Obviously a permanent magnet may be substituted for the electromagnet shown, or the tube may be disposed within a coil of wire carrying an electric current.

The cathodes 1 and 21 of Figs. 1 and 2 do not begin to emit copiously until the temperature is raised to a certain point. Beyond this point the thermionic emission increases very rapidly with temperature.

Fig. 3 shows another embodiment of the invention and includes an auxiliary heater 31a placed close to the cathode 31 so as to raise the temperature of the cathode to the point at which the thermionic emission sets in. The heat from the external source is permitted to raise the temperature of the cathode so that the heat brought from the external focusing surface S serves to raise the temperature only above this "bias-point" instead of from room temperature only. The sensitivity of the device is thus enhanced by the addition of this auxiliary heater. The cathode and heater assembly may be constituted by an orificed surface 31b which may be rectangular or annular in shape. The silver foil 31 constituting the emissive surface extends over the orifice and is anchored by any convenient means to this surface 31b. The auxiliary heater 31a is enclosed within a tubular shield 31c which may be accommodated in a dependent portion 31d, of the tube.

It is necessary to maintain each of the lower multiplying electrodes positive with respect to the primary electron source and with respect to any electrode between it and the said source. For this purpose (referring to Fig. 3) the cathode 31 may be connected to the negative terminal of a source of unidirectional potential, exemplified in the drawing by battery B and resistor R, and the output electrode 42 may be connected to the positive terminal of the source through an output device 44. The first multiplying electrode 33 may be connected to a positive point 33a on the resistor R and each of the remaining multiplying electrodes 35, 37, 39 connected to successively more positive points 35a, 37a, 39a on the resistor.

The accelerating electrodes may each be maintained at the same potential as the next succeeding lower multiplying electrode and for this connecting leads "l" may be provided within the tube. The accelerating electrode 40 is connected to a point 40a more positive than point 39a and the output or collector electrode 42 is connected to a point 42a of still higher potential.

If heat rays, such, for example, as emanate from a furnace are focused as by a reflector S or by any other suitable means, upon the cathode 31, thermionic-electrons will be emitted propor-

tionally thereto. These thermionic-electrons will be accelerated toward the upper electrode 32 directly above the cathode 31 because of the electrostatic field and, if no magnetic field were present, they would impinge thereon. However, the magnetic field (not shown in Fig. 3), which is parallel to the planes of the electrodes, subjects the electrons, moving toward the accelerating electrode, to a force component at a right angle 10 to their instantaneous direction of travel. If the electric and magnetic fields are adjusted to proper values, the electrons will describe trochoidal paths and will strike the first multiplying electrode 33.

15 Electrode 33 is maintained at a potential positive with respect to the cathode 31 and the thermionic-electrons striking it will cause the emission of secondary electrons. The secondary electrons are in turn accelerated toward the second 20 upper electrode 34, but, by reason of the magnetic field, they will be diverted and be focused upon the third lower electrode 35. Here again a multiplication, by reason of secondary emission, is secured and this process is repeated in the remaining stages 37 and 39, until the amplified 25 stream of secondary electrons is collected by the output electrode 42 and the resultant current caused to actuate a meter, relay or the like exemplified in the drawing by device 44 included be-

tween the output electrode 42 and the positive terminal 42a of the potential source.

If a meter is employed it may be calibrated in degrees of temperature as indicated at 44a. If a sufficient number of multiplying stages are employed to provide sufficient power output the device may be utilized to directly actuate a motor driven fuel feed or other thermal control forming part of the system with which the device of the invention is associated.

What is claimed is:

1. A heat responsive device comprising an evacuated envelope containing a radiant-heat responsive electron-emissive cathode constituted essentially of silver foil of a thickness of the order of .0002 of an inch, means for multiplying electrons from said cathode, and a collector electrode upon which said multiplied electrons impinge. 15

2. A heat responsive device comprising an evacuated envelope containing a radiant-heat responsive electron-emissive cathode comprising a mica base having an evaporated silver film thereon, means for multiplying electrons from said cathode, and a collector electrode upon 25 which said multiplied electrons impinge.
